UNITED STATES PATENT OFFICE.

THOMAS J. STANTON, OF LITTLE ROCK, ARKANSAS.

SAND-BOX.

SPECIFICATION forming part of Letters Patent No. 610,590, dated September 13, 1898.

Application filed March 8, 1898. Serial No. 673,120. (No model.)

To all whom it may concern:

Be it known that I, THOMAS J. STANTON, a citizen of the United States, residing at Little Rock, in the county of Pulaski and State of 5 Arkansas, have invented certain new and useful Improvements in Sand-Boxes; and I do hereby declare the following to be a full, clear, and exact description of the invention, such as will enable others skilled in the art to which 10 it appertains to make and use the same.

This invention has reference to a novel construction in sand-boxes and mechanism for delivering the sand to rails or other points where it is needed, and is adapted, more especially, for use in connection with locomotives, the object being to provide devices by means of which the sand can be effectively delivered and which prevents the clogging of 20 the sand within the sand-pipe or sand-box by reason of moisture, waste, or other foreign matter.

The invention consists in features of construction hereinafter fully described and specifically claimed.

25 In the accompanying drawings, forming a part of this specification, Figure 1 is a side elevation, partially in vertical section, of a sand-box and accompanying devices constructed in accordance with this invention.

30 Fig. 2 is a top plan of the bottom of the sand-box. Fig. 3 is a bottom plan of the same. Fig. 4 is a vertical section, taken on an enlarged scale, of the lower end of the sand-box and the sand-pipe. Fig. 5 is a detail section 35 showing the chain brush lowered. Fig. 6 is a detail perspective of a section of the chain brush.

Referring now to said drawings, 1 indicates the sand-box, which may be of any approved 40 construction and which is provided at opposite sides with openings 2, from which lead the sand-pipes 3. These sand-pipes extend downwardly on both sides of the locomotive and are provided at their lower ends with nozzles 4, that are situated to deliver the sand to the rail and in front of the wheel. The upper end portion of the nozzles 4 is straight, as shown at 5, while the lower end portion is curved to the rail, and the joint between the 45 nozzles and the lower end of the sand-pipe 3 is preferably screw-threaded, as shown, provided, however, with a removable set-screw

6, that fastens the lower end of the sand-pipe and the upper end of the nozzle in the manner shown. The openings 2 in the bottom of 55 the sand-box are controlled by the valves 7. These valves are pivoted at one end and slide upon the bottom of the box, being provided at one side with openings 8, which when situated above the openings 2 in the bottom of 60 the box permit the sand to pass into the sand-pipe. The upper face of the valve is provided with a plurality of teeth 9, that extend in the direction in which the valves move to open the box, so as to carry to one side waste, 65 clogged sand, or other matter that may prevent the further entrance of the sand into the openings 8, as is obvious. The inner end of the valve is rigidly secured to a rotatable pin 10, that passes through the sand-box and projects below the lower end thereof. Secured to these pins 10, below the bottom of the box, 70 are arms 11, that extend to one side and are connected on their outer ends by a bar 12, that is pivoted to both of the arms, whereby 75 the valves are caused to move in unison. The arm 11 at one side of the sand-box is provided with a laterally-extending portion 13, that is pivotally connected with the forward end of the operating-rod 14, that extends rearwardly into the cab of the locomotive, as shown. The rear end of this rod 14 is provided with a toothed portion 15, whereby the 80 rod can be held in retracted position by a pawl 16, so as to regulate the extent to which 85 the valve is open and also for the purpose of holding it in its position.

Situated within the sand-pipe and nozzle is a chain brush 17 and a scraper 18. The chain brush is connected with the valve and 90 extends downwardly and into the nozzle, while the scraper 18 is connected with the lower end of the chain brush and is curved to conform with the curvature of the lower end of the nozzle. The said chain brush 95 and scraper are adapted to be raised when the valve is open, so as to loosen the sand within the sand-pipe and nozzle and to effectually prevent clogging. The connection between the chain brush and the valve comprises a link 19, the upper end of which is pivoted within one end of the recess 20 in the lower side of the valve, while its lower end is pivoted to the upper end of the chain 100

brush. Said link 19 fits within the said recess 20, and the parts are so arranged that when the valve is open the link is raised and passes into the recess, whereby the chain brush is raised to an extent equal to the length of the link. The said chain brush is composed of a plurality of links 21 and 22. Each of these links is provided with a winged head 23, having rearwardly-extending lugs 24 on their outer ends, the said winged head being connected to the body of the link by a shank 25. In the body of the link is the slot 26 to receive the winged head of another link, while the body of the link is itself provided with wings 27, the outer edges of which are curved to the rear and terminate at their rear ends in pointed projections 28. The wings 27 upon the links 21 are bent to extend substantially at right angles to the body portion of the link 20 and in opposite directions to the wings on the adjoining links 22. The connection between the upper link of the chain brush and the link 19 comprises a flat link 29, having a slot 30 at one end to receive the head 23 of the upper link of the chain brush, while the other end of the link 29 is provided with eye-lugs 31, between which the lower end of the link 19 is pivoted.

It is seen from the foregoing description that the chain brush consists of a plurality of winged links wherein the wings on alternate links extend in opposite directions, so that when the chain is moved within the sand-pipe it effectually cuts and breaks the mass of sand and prevents clogging.

The lower end of the chain brush when the valve is closed extends to the upper end of the curved portion of the nozzle, and the scraper 18, which consists of a shank 32, having laterally-extending wings 33, and which is tapered toward its lower end, is connected with the lower end of the chain brush by means of a loop 34, that passes through the slot in the lower link of the chain brush and between the ends of which the upper end of the scraper is secured. Fastened upon the said loop 34 is a ring 35, that fits within the straight portion of the nozzle. A spring 36 is situated within the straight portion of the nozzle and bears at its opposite ends against the ring 35 and the lower end of the sand-pipe, which is situated within the upper end of the nozzle.

Near the upper end of the nozzle is a port 37, from which leads an inclined pipe 38, that communicates with a source for supplying steam or compressed air, whereby a downward blast can be generated within the nozzle to not only prevent the sand from clogging between the convolutions of the spring 36, but also serves to create a pressure-vacuum above the port 37 to feed the sand into the nozzle and also gives blast to force it through the nozzle.

In operation it is seen that when the operating-rod 14 is moved to open the valve the links 19 elevate the chain brush and scraper

for the purpose above described and permit the sand to pass into the sand-pipe, while the blast from the pipe 38 forces the sand through the nozzle. When the operating-rod is released and the valves close, the weight of the chain brush and scraper, together with the force of the springs 36, draws the chain brush and scraper to their normal position and to the lower limit of their movement.

Having thus described the invention, what is claimed as new is—

1. The combination with a sand-box provided with openings in the bottom thereof, sand-pipes leading from said openings, and nozzles at the lower end of said sand-pipe, of valves controlling said openings in the bottom of the sand-box, an operating-rod for said valves, movable chain brushes and scrapers situated within said sand-pipes and nozzles and connected at their upper ends with the valves so as to be raised when the valves are open, and to be lowered when the valves are closed, and means for creating a blast in said nozzles.

2. The combination with a sand-box having an opening in the bottom thereof and a sand-pipe leading from said opening, of a valve pivoted to slide upon the bottom of said sand-box and to control said opening, means for sliding said valve, a recess in the lower side of said valve, a link having one end pivoted within said recess, and a chain brush situated within the sand-pipe and connected with the other end of said link.

3. The combination with a sand-box having a depending sand-pipe provided at its lower end with a nozzle, of a valve for controlling the upper end of the sand-pipe, a chain brush connected with said valve and extending into the sand-pipe and provided at its lower end with a scraper situated within the lower end of the nozzle, a spring for depressing said chain brush and scraper, and a blast-pipe communicating with said nozzle.

4. The combination with a sand-box having a sand-pipe and a nozzle at the lower end of the sand-pipe, a valve for controlling the upper end of said sand-pipe, a chain brush connected with said valve and extending into said sand-pipe, a scraper at the lower end of the chain brush extending to the lower end of the nozzle, a ring secured to the lower end of said chain brush, a spring situated within the nozzle and bearing at its opposite ends against said ring and the lower end of the sand-pipe, and a blast-pipe communicating with the lower end of the sand-pipe.

5. A chain brush for the purpose set forth comprising a plurality of links yieldingly connected together and provided with laterally-extending wings, the wings on one link extending at right angles to the body of the link and in the opposite direction from the wings of the adjoining links.

6. A chain brush for the purpose set forth comprising a plurality of links, each of said links comprising portions having a winged

head at one end, a slot at the other end, and laterally-extending wings upon said body portion.

7. A chain brush for the purpose set forth comprising a plurality of links each of said links comprising a body portion having a winged head connected therewith by a shank and provided with rearwardly-extending lugs, a slot in the rear end of said body por-

tion, and laterally-extending tapering wings to upon said body portion.

In testimony whereof I affix my signature in presence of two witnesses.

THOMAS J. STANTON.
